UNITED STATES PATENT OFFICE.

HUGH McNALLY, OF RICHLAND CENTER, WISCONSIN.

FOLDING POCKET-HATCHET.

942,342.

Specification of Letters Patent.

Patented Dec. 7, 1909.

Application filed November 4, 1908. Serial No. 461,068.

To all whom it may concern:

Be it known that I, HUGH McNALLY, a citizen of the United States, residing at Richland Center, in the county of Richland and State of Wisconsin, have invented a new and useful Folding Pocket-Hatchet, of which the following is a specification.

It is the primary object of the present invention to provide a tool such as a hatchet or ax having a foldable handle so constructed and arranged as to protect and cover the edge of the blade of the tool when the handle is folded.

One of the novel features of the invention resides in the means employed for holding the handle sections rigidly in unfolded position so that the tool may be manipulated as readily as if the handle were integral throughout.

Another novel feature of the invention resides in the means employed for locking the handle sections in folded position so that when the tool is carried in the pocket, there will be no likelihood of the sections moving to unfolded position and thereby exposing the cutting edge of the blade of the tool.

A still further feature of the invention resides in the novel manner of securing the handle to the blade of the tool.

Other novel features and objects will be made apparent in the specific description which is to follow.

In the accompanying drawings, Figure 1 is a view in side elevation showing the tool in unfolded position or in other words in position for use, Fig. 2 is a vertical longitudinal sectional view in detail through the intermediate portion of the handle of the tool showing the handle sections in unfolded position. Fig. 3 is a view similar to Fig. 1 but showing the tool folded, Fig. 4 is a view similar to Fig. 2 with the handle section in folded position, Fig. 5 is a transverse sectional view on the line 5—5 of Fig. 3, showing the means provided for locking the handle sections in folded position, and Fig. 6 is a view similar to Fig. 5 on the line 6—6 of Fig. 3.

As shown in the drawings, the tool embodying my invention is comprised, broadly speaking, of a blade indicated in general by the reference character A and a handle indicated in general by the reference character B. The handle B is made up of a pair of sections one of which is indicated by the numeral 10 and the other by the numeral 11,

and both of these sections are of channel formation or more specifically speaking, are U-shaped in cross section. The section 10 is provided at one end of each of its walls with a pivot ear 12, and the other section, 11, is received at the corresponding end between these ears and is held pivotally in this relation by means of a pivot pin 13, it being understood that the handle sections 10 and 11 are in this manner connected so that they may be folded one upon the other.

As clearly shown in Fig. 6 of the drawings, the blade A of the tool, which blade may be in the form of a hatchet or ax head, is provided in each of its side faces with a seat 14, and the section 10 of the handle of the tool has the bottom of its channel omitted for a short distance extending inwardly from the end opposite the pivoted end thereof so as to form spaced members or furcations 15 which are received in the seats 14, straddling the rear edge of the blade, and are secured in this position with their outer faces flush with the said side faces of the blade, by means of a stud bolt or other pivotal fastening means 16, it being understood that by countersinking the face portions 15 in the blade as above described, the securing bolt 16 is relieved almost entirely of strain when the tool is in use.

As shown in the drawings, the handle end of the section 11 of the handle of the tool has the walls of its channel spaced apart a distance greater than the remainder of the length of its walls, and the outer surface of this portion of each channel wall is roughened as at 17 to afford a gripping surface. This portion of the section 11 of the handle of the tool is preferably of a length equal to the length of the cutting edge of the blade, and as will be readily understood from an inspection of the drawings, when the said section is swung to folded position, the cutting edge of the blade will be received therein. It will thus be understood that when the handle sections are folded, the cutting edge of the blade will not only be protected, but it will be prevented against injuring the material of a pocket in which it is being carried. In order to obviate dulling of the blade due to contact of the bottom of the channel of the section 11 with the cutting edge thereof, I provide in this portion of the channel of the said section a bed 18 of lead or other soft metal.

As a means for holding the sections rigidly

in unfolded position, I provide a latch upon one of the members and a stop upon the other member of the handle, and the stop just mentioned is in the form of a pin 19, which is secured at its ends in the walls of the channel of the member 10, extending transversely of the said channel, and has its side which is presented in the direction of the pivot 13 for the handle sections, flattened as indicated by the numeral 20. The latch member for engaging the stop is indicated in general by the reference numeral 21 and is preferably of channel formation and, as in the case of the handle sections, U-shaped in cross section. This member is pivoted at one end between the walls of the channel of the member 11 of the handle by means of a pivot pin 22 and, when the handle sections are in unfolded position, extends with the bottom of its channel substantially coincident with the edges of the channel walls of the two sections 10 and 11 as clearly shown in Fig. 2 of the drawings. The walls of the latch member 21, at their free ends, are cut at an angle as indicated by the numeral 23, and when the handle sections are in unfolded position, the said end edges of the said walls of the latch member engage or abut against the flattened side 20 of the stop pin 19, thereby preventing folding of the handle section 11 upon the section 10.

As shown in Figs. 3 and 4 of the drawings, when the handle section 11 is folded upon the section 10, the latch member 21 rides over the said stop pin 19 and between the same and the bottom of the channel of the member 10 of the handle. A wire spring 24 is coiled intermediate its ends as at 25 around the pivot pin 13 for the handle sections 10 and 11, and this spring bears with one of its arms against the bottom of the channel of the section 10 and with its other arm against the bottom of the channel of the latch member 21, the function of this spring being to hold the latch member at all times in engagement with the stop pin either at the bottom of its channel or, as shown in Figs. 3 and 4 of the drawings, or at its free end as shown in Figs. 1 and 2 of the drawings. It will be understood in connection with the foregoing description, that not only does the spring 24 serve to hold the latch member 21 at all times in engagement with the stop pin 19, but that when the sections are completely unfolded, the said latch member will be forced by the spring to drop with its free end in engagement with the said stop pin. In order to fold the sections after they have been unfolded, it is of course necessary to press inwardly against the latch member 21 and in order that this may be readily accomplished, I notch the edges of the walls of the channel of the section 10 of the handle as indicated by the numeral 26 and roughen the corre-

sponding portion of the latch member 21 as indicated by the numeral 27.

As a means for holding the handle sections locked in folded position, I provide in each wall of the channel of the section 10 of the handle an indentation 28 and when the sections are moved to folded position, the threaded end of the pivot pin 22 for the latch member 21 of the tool will snap into these indentations and perform the function stated.

From the foregoing description of my invention, it will be seen that I provide a tool of the class described which is simple in construction and extremely durable and cheap to manufacture, and it will be noted that the means employed for holding the handle sections of the tool rigidly in unfolded position, is very substantial and that accidental folding up of the sections, which would likely result in injury, is entirely obviated by the means shown and described.

What is claimed is:—

1. In a tool, a handle comprised of foldable sections, a blade carried by one section, a transverse pin upon one section, and a latch pivoted to the other section and formed to engage with the pin when the sections are in unfolded position to hold the said sections in said position, and to ride over the said pin when the sections are folded.

2. In a tool, a handle comprised of foldable sections, a blade carried by one section, a transverse pin carried upon one section and having a flattened surface, and a latch pivoted to the other section and provided with an inclined end adapted to engage with the flattened surface of the pin to hold the sections in unfolded position.

3. In a tool, a handle comprised of foldable sections, a blade carried by one section, a transverse pin carried by the other section and provided with a flattened surface, and a latch pivoted to the other section and provided with angularly cut ends engageable with the flattened surface of the pin to hold the sections in unfolded position, the said latch being adapted to ride over the said pin upon folding of the sections.

4. In a tool, a handle comprised of foldable sections, a blade carried by one section, the said sections being of channel formation, a flattened pin extending transversely of the channel of one member, and a latch pivoted between the sides of the channel of the other member and working in the channel of the first mentioned member above the pin, the said latch being arranged to engage at its end with the flattened side of the pin when the sections are in unfolded position.

5. In a tool, a handle comprised of foldable sections, a blade carried by one section, the said sections being of channel formation, a pin extending transversely of the

channel of one section, and a channeled latch member pivoted in the channel of the other section and extending into the channel of the first mentioned section and riding over the pin, the said latch member being arranged to engage at its end with the pin when the sections are in unfolded position.

5 6. In a tool, a handle comprised of foldable sections, a blade carried by one of the sections, a stop carried by one of the sections, a pivoted latch member carried by the other section, and arranged to ride over the said stop and to engage at its end with the stop when the sections are in unfolded position, 10 and a spring engaged with said latch member for holding the same at all times in engagement with the stop.

15 7. In a tool, a handle comprised of foldable sections, a blade carried by one of the sections, the said sections being of channel formation, a stop extending transversely of one of the sections, a latch member pivoted in the channel of the other section and extending in the channel of the first mentioned section resting in engagement with the stop, 20 said latch member being arranged to engage at its end with the stop when the sections are in unfolded position, and a spring engaging the latch member and holding the 25 same at all times in engagement with the stop.

30 8. In a tool, a handle comprising foldable sections, a blade carried by one of the sections, said sections being of channel formation, a channeled latch member pivoted in the channel of one of the sections, a stop extending transversely of the channel of the other section, said latch member projecting at its free end into the channel of 35 the last mentioned section and resting in engagement with the stop, and a spring seating in the channel of the second mentioned member and in the channel of the latch member for holding the said latch 40 member at all times in engagement with the said stop.

45 9. In a tool, a handle comprised of foldable sections, a blade carried by one of the sections, the said handle sections being of channel formation, a stop extending transversely of the channel of one of the sections, a channeled latch member pivoted in the channel of the other section and extending into the channel of the first mentioned sec-

55 tion and resting in engagement with the said stop, and a spring having diverging arms and secured fixedly at the junction of its arms, one arm bearing in the channel of the first mentioned member and the other arm bearing in the channel of the latch member.

60 10. In a tool, a handle comprised of foldable sections, a blade carried by one of the sections, a pivot pin connecting the sections, a stop carried by one of the sections, a latch pivoted to the other section and resting in engagement with the stop, and a spring fixedly connected with the pivot pin and including diverging arms engaging with the first mentioned member and with the latch to hold it in constant engagement with the 65 stop.

70 11. In a tool, a handle comprised of foldable sections, a blade carried by one of the sections, a stop carried by one of the sections, a latch member pivoted to the other section and engageable with the stop to hold the sections in unfolded position, the 75 said latch member being adapted to ride over the stop when the sections are folded, the wall of the channel of the first mentioned section being provided with an indentation, and the said pivot for the latch member being adapted to seat in said indentation when the sections are in folded position.

80 12. In a tool, a handle comprised of foldable sections, a blade carried by one section, said sections being of channel formation, a stop extending transversely of the channel of one section, a latch member pivoted to 90 the channel of the other section and extending into the channel of the first mentioned section and resting in engagement with the stop, and a spring pressing against the said latch member to hold it in such engagement 95 with the stop, the edges of the walls of the channel of the first mentioned member being notched at a point coincident with the free end of the latch member so that the latch member may be depressed.

100 In testimony that I claim the foregoing as my own, I have hereto affixed my signature in the presence of two witnesses.
